UNITED STATES PATENT OFFICE.

CHARLES FAYER, OF NEW YORK, N. Y., ASSIGNEE TO WAPPLER ELECTRIC CO., INC., A CORPORATION OF NEW YORK.

HIGH-TENSION ELECTRIC MACHINE.

1,348,986.

Specification of Letters Patent. Patented Aug. 10, 1920.

Application filed June 26, 1919. Serial No. 306,813.

To all whom it may concern:

Be it known that I, CHARLES FAYER, a citizen of the United States, residing at New York city, county of Bronx, and State of New York, have invented certain new and useful Improvements in High-Tension Electric Machines, of which the following is a full, clear, and concise description.

My invention relates to high tension electric machines, of a type suitable for use in connection with X-ray tubes and the like, and in which a rectifying disk is used in connection with a high tension transformer.

More particularly stated, my invention contemplates a high tension electric machine of the kind just mentioned, and in which I give the various parts such form and arrangement as to render them readily accessible, as well as to a great extent removable and replaceable independently of each other.

My invention further contemplates the arrangement of the various parts in such relative positions as to improve the insulation of the various conducting members.

In addition, my invention comprehends the collection of the parts in such manner as to promote strength, simplicity and compactness, combined with increased efficiency.

Reference is made to the accompanying drawing forming a part of this specification, and in which the various parts are designated by reference numerals, the figure being a perspective of my device with certain parts broken away.

A cabinet 1 is provided with a door way 2 and with a door 3 as well as with a top 4. These parts are usually made of wood, but may be constructed of other material should occasion so require. The cabinet is provided with a removable glass or bakelite plate window 5.

Located within the cabinet is an iron table 6, secured rigidly in position by aid of braces, one of which is shown at 7.

Below the table 6 is a transformer 8 the secondary of which supplies the high tension currents to be rectified.

Resting upon the iron table 6 and detachably secured thereto by bolts 9 is a synchronous motor or rotary converter 10. This motor is provided with a massive bearing 11 and with an armature shaft 12 which extends through this bearing and to a distance of several inches therefrom.

The armature shaft 12 carries a hub 13 having the form of an annular flange.

A rectifying disk is shown at 14, and is made of insulating material, usually mica-nite. This disk turns with the shaft and for currents of sixty cycles per second makes eighteen hundred revolutions per minute.

In order to mount the disk 14 upon the armature shaft, I provide bolts 15 which extend through holes in a clamping plate 16 and into engagement with the head 13. By removing the bolts, the disk 14 may be readily detached, and by replacing the bolts the disk may be again secured upon the shaft. The window 5 is removable in order to facilitate access to the disk 14 and other parts to be removed.

The rectifying disk 14 carries a pair of sectors 17, made of conducting material and connected by a wire or metallic strip 18; also another pair of sectors 19, similarly connected by a wire or strip 20.

Disposed adjacent the path of travel of the sectors 17, 19 are four brushes 21, 22, 23, 24, supported by four posts 25, 26, 27, 28 of insulating material, such as hard rubber or vulcanite.

The post 26 is mounted upon a standard 29, which is made of metal and detachably secured by a bolt 30 to the table 6. The post 28 is mounted upon a metallic standard 29^a, similar to the standard 29 and like the latter detachably secured to the table 6. The post 25 is mounted upon a beam 31, made of metal and secured to the metallic posts 29, 30. The beam 30 has substantially the general form of an inverted V. The post 27 is secured to a metallic bracket 32, which is mounted upon the under side of the table 6. This bracket, like the standards 29 and 30, is substantially flush with the adjacent edge of the table 6, so that the posts 25, 26, 27, 28 each extend out toward the window 5, for some little distance from the general vertical plane of the table 6.

The armature shaft 12 is of such length as to support the disk 14 in a vertical plane a little to the right of the brushes 21, 22, 23, 24, according to the figure.

Thus the disk 14 is spaced far enough from the table 6 to prevent all danger of sparks leaping from the disk or from any posts carried by it to the metallic table or any of the various metallic posts mounted thereon. Thus by placing the disk 14 at a safe dis-

tance from the table, the disk is disposed nearer to the window 5, and hence, more readily accessible for purposes of removal and replacement.

5 Connected with the secondary of the transformer 8 are two leads 33, 34, which extend through two insulators 35, 36 which are mounted upon wooden arms 37, 38, these arms being detachably secured to the metallic table 6. The leads 33, 34, are connected to the brushes 22, 24. A lead 35 is connected to the brush 21 and to a post 40 made of insulating material, and through which extends a conductor 41. A similar post 42 is 10 connected to a lead 43, and a conductor 44, which may be a part of the lead 43, extends through this post. The lead 43 extends through a wooden arm 43, supported by the table, and is provided with a portion 46 15 which is connected to the brush 23.

20 The rectified currents are taken from the conductors 41, 44, at the top of the cabinet.

The manner in which the high tension currents are rectified forms no part of my 25 present invention, and is accomplished in the usual manner by the action of the rectifying disk and the synchronous motor actuating the same.

20 The operation of my device may be readily understood from the foregoing description.

35 The transformer 8 and the synchronous motor 10 being in action, the high tension currents are induced in the secondary of the transformer and are rectified as above mentioned. No sparks can leap from the disk to the table or to any metallic part carried by or immediately associated with the table.

40 If, however, the window 5 be removed the parts are readily accessible. The disk may be removed, and for this purpose is disengaged from the hub 13 and armature shaft by merely taking out the bolts 15.

45 The standards 29 and 30 may be quickly and easily detached from the table, and removed along with the beam 31, the leads 33, 34 being disconnected for this purpose. Thus the standards 29, 30 and the beam 31 50 may together be considered as a frame, having roughly an arcuate form and removable bodily with the posts 25, 26, and 28.

55 By taking out the bolts 9 the motor 10, carrying the armature shaft 12 and the disk 14, may be removed without disturbing the frame consisting of the standards 29, 30 and the beam 31. Similarly the removal of this frame is accomplished without disturbing the motor or the disk.

60 The wooden arms 37, 38, 45 are easily taken out, or disconnected from the parts to which they are secured.

It will be noted that by my arrangement of the parts the insulation is greatly im-

proved, since all of the metallic parts are 65 so spaced and arranged that while great differences in potential may be developed between different metallic parts, no great difference in potential can develop between any two metallic parts located close together. 70 An important feature of the invention is adequate spacing between such metallic parts as are subjected to excessive differences in potential.

The posts are also arranged in such manner as to prevent leakage of current and to avoid as far as practicable the development of all conditions tending to subject the posts to undue electric strain, even when my device is used for long periods of time or subjected to moderate degrees of dampness or employed under climatic conditions tending to invite a breakdown.

It will also be noted that my arrangement promotes great strength, stability, efficiency 85 and compactness.

I do not limit myself to the precise arrangement shown, as variations therefrom can be made within the scope of my claims.

90 I claim:

1. In a high tension electric machine the combination of a metallic table, a plurality of supporting members secured thereupon and disposed adjacent one edge thereof, posts of insulating material mounted upon said supporting members and extending away from said edge of said table, brushes mounted upon said posts and thus spaced away from said table and from all metallic parts in immediate proximity thereto, a synchronous motor mounted upon said table and provided with an armature shaft extending away from said table, and a rectifying disk mounted upon said armature shaft and provided with conducting members rotating in a plane disposed adjacent said brushes.

2. In a high tension electric machine the combination of a cabinet provided with a window, a table disposed within said cabinet, a synchronous motor detachably mounted upon said table and located adjacent said window so as to be readily removable through said window when detached from said table, a rectifying disk 110 located within said cabinet and connected with said motor so as to be actuated thereby, a frame detachably mounted upon said table, posts mounted upon said frame, and brushes carried by said posts and co-acting 115 with said rectifying disk for the purpose of rectifying electric currents, said frame with said posts and brushes being as a unit so located as to be readily removable as a unit through said window independently of said 120 motor.

3. In a high tension electric machine the combination of a cabinet, a supporting

- table located within said cabinet, a synchronous motor mounted upon said table and provided with a revoluble shaft projecting over one edge thereof, a frame mounted upon said table and disposed adjacent said edge thereof, posts of insulating material mounted upon said frame and projecting over said edge of said table, brushes carried by said posts, a revoluble rectifying member carried by said shaft and co-acting with said brushes for the purpose of rectifying electric currents in synchronism with said motor, said revoluble rectifying member being spaced from said supporting table by a distance sufficient to prevent sparking as between said disk and said table.
4. In a high tension electric machine the combination of a metallic supporting table, an arm detachably mounted upon the under side thereof, a post carried by said arm and extending beyond the edge of said table, a pair of standards detachably mounted upon said table, a frame member mounted upon said standards and together therewith constituting a frame, a plurality of posts mounted upon said frame, brushes mounted upon said last mentioned posts and upon said first mentioned post, all of said brushes being arranged substantially in a vertical plane, a synchronous motor mounted upon said table and provided with a revoluble shaft extending beyond said edge of said table and substantially parallel with ends of said posts, a rectifying disk mounted upon said revoluble shaft, and co-acting with said brushes for the purpose of rectifying currents, said disk occupying a plane substantially parallel with said plane in which said brushes are mounted.
5. In a high tension electric machine the combination of a table and arm mounted upon the under side of said table, a pair of standards mounted upon the upper side of said table, a frame member secured to said standards, posts of insulating material mounted upon said standards and said frame member and also upon said arm, brushes carried by said posts and a rectifying disk revolubly mounted adjacent said brushes and provided with contact mechanism co-acting with said brushes for the purpose of rectifying electric currents.
6. In a high tension electric machine the combination of a metallic table, a pair of metallic standards mounted upon said table and disposed adjacent one edge thereof, a frame member mounted upon said standards and together therewith constituting a frame, an arm mounted upon the under side of said table, a post of insulating material mounted upon said arm and extending past said edge of said table, other posts of insulating material mounted upon said frame and each projecting past said edge of said table, a brush mounted upon each post, all of said brushes being disposed substantially in a vertical plane, a synchronous motor mounted upon said table and provided with an armature shaft having sufficient length to extend beyond said edge of said table and a rectifying disk mounted upon the outer end of said shaft and disposed adjacent the plane in which said brushes are located.

CHARLES FAYER.
